UNITED STATES PATENT OFFICE.

HENRY E. STREIBER, OF CANTON, OHIO, ASSIGNOR TO THE SUN VAPOR AND GAS STREET LIGHT COMPANY, OF CANTON, OHIO, A CORPORATION OF WEST VIRGINIA.

VALVE.

1,209,226.

Specification of Letters Patent. Patented Dec. 19, 1916.

Application filed May 20, 1914. Serial No. 839,746.

To all whom it may concern:

Be it known that I, HENRY E. STREIBER, a citizen of the United States, residing at Canton, in the county of Stark and State of Ohio, have invented certain new and useful Improvements in Valves, of which the following is a specification.

The invention relates to a valve for controlling the flow of gas to a plurality of 10 burners, as for instance, a cluster of lamps upon a post for street illumination. One lamp of such a cluster is usually located on the top of a post, and the remainder of the lamps are frequently located on the ends 15 of arms extending radially from the post below its upper end.

When a full illumination is desired during the forepart of the night, it is customary to burn all of the lamps at the same time; 20 but when only a partial illumination is necessary after midnight, it is desirable to extinguish all the lateral lamps of the cluster, leaving burning only the one at the top of the post; and finally at daybreak, for the 25 purpose of economy, it is necessary to extinguish the remaining top burner, so that until evening the supply of gas will be shut off from all the lamps. It will be understood that a pilot light is constantly burning for 30 each lamp, so that the same will be automatically ignited when the valve controlling the supply of gas thereto is opened.

The object of the present invention is to provide a three-position valve, by means of 35 which the attendant can control the supply of gas to the several burners, at the three stated periods and for the purpose indicated, by the mere manipulation of a handle or lever suitably positioned on the post. This 40 object is attained by providing a valve case with two ports on one side, both communicating with the gas supply pipe, and two ports on the opposite side, leading respectively to the single lamp and to the lateral 45 lamps; and by providing a hollow valve in the case, with a plurality of ports arranged with reference to the case ports, so that in each of the three defined positions of rotation, gas will be supplied first, to all the 50 burners; or second, to the single burner only; or third, will be shut off from all the burners.

The invention also includes certain mechanism by which the valve is operated, where- 55 by the same can be readily manipulated by

an attendant to set the valve in one of its three specific positions.

A preferred embodiment of the invention is illustrated in the accompanying drawing, forming part hereof, in which—

Figure 1 is a perspective view of a cluster of three lamps on a post, showing the general arrangement of the same; Fig. 2, a fragmentary section of the same, showing the arrangement of the valve and gas pipes 60 within the post and the lateral arms thereof, the valve being turned for supplying gas to all the lamps; Fig. 3, a perspective view of the valve and adjacent parts, showing the valve case in section, the parts being positioned as in Fig. 2, for supplying gas to all 65 the lamps; Fig. 4, a sectional view of the valve and its case with the connected pipes, showing the valve rotated to the position for supplying gas to one lamp only; Fig. 5, 70 a similar sectional view showing the valve rotated to the position for stopping the flow of gas to all the burners; Fig. 6, a perspective view showing details of the operating 75 crank arm; and Fig. 7, a sectional view of 80 the same.

Similar numerals refer to similar parts throughout the drawings.

The gas supply pipe 1 rises centrally in 85 the post 2, which post has the single lamp 3 mounted on the top and two or more lamps 4 depending from a like number of lateral arms 5 extending radially from the upper end of the post below the top lamp 3.

The lower end of the valve case 6, is secured on the upper end of the gas supply pipe 1, and in the upper end of the valve case, is secured the nipple 7, to which is secured the cross fitting 8, in the lateral branches of which are secured the lateral 90 pipes 9, leading to the lateral lamps 4 of the cluster. In the upper end of the valve case 6, is also secured the lower end of the top lamp pipe 10, which extends upward freely, through the nipple 7, and the cross fitting 8, 100 to the single lamp at the top of the post; a suitable packing 8^a, being provided in the upper branch of the fitting around the pipe 10, to close and seal the annular opening between them.

The body of the valve case is cylindric, or preferably slightly conical in shape as shown, and forms the conical seat 11 for the similarly shaped valve 12; which valve is rotatable in the case on a transverse axis there- 110

of, and may be retained therein by means of the washer 13, the bolt 14, and the nut 15, or like means.

In the lower side of the case, are provided 5 the two ports 16 and 16^a, one of which ports 16, is centrally located in the vertical axis of the case, corresponding to the axial alinement of the gas supply pipe 1, below, and the single gas pipe 10 above; and the other 10 of which ports 16^a, is located at a lateral interval from the central port, in the vertical plane passing through the axis of the valve as shown in the several sections. Both of these ports communicate with the gas supply 15 pipe 1, as by means of the intervening chamber 17 formed in the lower end of the valve case.

In the upper side of the case, are provided the two ports 18 and 18^a, one of which 20 ports 18, is centrally located in the vertical axis of the case, and communicates directly and solely with the top lamp pipe 10 above; and the other one of which ports 18^a, is located at a lateral interval from the central 25 port, in the vertical plane passing through the axis of the valve, and communicates with the nipple 7, leading through the fitting 8 to the lateral lamp pipes 9. The port 18^a is deflected and enlarged in the upper end of 30 the case to surround the pipe 10, leading to the top lamp.

The conical valve 12 is provided with the central hollow or cavity 19, and in the lower side of the valve, when the same is rotated 35 to the position shown in Figs. 2 and 3, the single port 20 is provided, which registers with the port 16^a of the case; while in the upper side of the valve, when rotated to the same position, are provided the two ports 40 21 and 21^a, registering respectively with the ports 18 and 18^a of the case; so that in this relation of the parts, gas is free to flow from the gas supply pipe, through ports 20 and 16^a, thence through the hollow of the valve 45 and the ports 21 and 18 to the top lamp pipe 10, and also through the ports 21 and 18^a to the lateral lamp pipes 9. When the valve is rotated one-third turn, (in the direction of the arrow as shown in Fig. 3), to 50 the position shown in Fig. 4, the single port 22 is provided in the lower side and the single port 23 is provided in the upper side of the valve; which ports register with the ports 16 and 18 of the case, and afford direct communication, through the hollow of 55 the valve, from the gas supply pipe 1, to the single lamp pipe 10; at which time the port 18^a leading to the lateral lamps, is closed.

For the purpose of continuing the supply 60 of gas to the top burner, while the valve is being rotated the one-third turn from the first to the second position described above, the annular groove 24 is provided in the periphery of the valve from the port 21 to the 65 port 23 therein; and a corresponding annu-

lar groove 25, is provided in the periphery of the valve from the port 20 to a point about one-third of the way around the valve; so that a sufficient amount of gas will continue to flow through these grooves to 70 supply the single lamp until the valve is rotated into the position shown in Fig. 4, for supplying the same directly through the ports 16, 22, 23 and 18. By a further rotation of the valve by one-third of a complete 75 turn, to the position shown in Fig. 5, all the ports in the case are completely closed, so that the flow of gas from the supply pipe is stopped, until the valve is again rotated a final one-third turn to the position shown 80 in Figs. 2 and 3, whereupon all the lamps will be supplied as described above.

For conveniently rotating the burner into its three positions thus described, the axial stem 26 is extended from the valve, on the 85 end of which stem is secured the cam ratchet 27 provided with three equidistant stops 28 on its periphery. The crank arm 29 is pivoted on the valve stem by means of the ears extending along the sides of the cam 90 ratchet; and the spring detent 30 is provided in the crank arm which is adapted to successively engage the three ratchet stops.

The wire spring 31 is loosely coiled around the end of the valve stem and has one end secured to the adjacent lateral arm 5 of the post, while the other end is connected with the crank arm. These parts are so arranged that the energy of the wire spring serves to normally hold the crank arm upward 95 against the adjacent arm of the post, in which relation of the parts, the detent in the crank is just above one of the stops or shoulders of the cam ratchet.

When it is desired to rotate the valve one-third turn, the crank arm is rotated to a position extending directly downward from the valve stem and upon being released is returned upward into normal position by the energy of the wire spring. The crank arm is preferably provided with the hook 32 which may be engaged by a similar hook on the end of a rod carried by an attendant, and the downward rotation of the arm serves to rotate the valve by the engagement of the detent with one of the ratchet shoulders; the arrangement of the parts being such as to bring the valve into one of its three positions, when the crank arm extends directly downward from the valve stem, into which position it can be readily pulled by the attendant.

While two ports 16 and 16^a are shown in the lower wall of the case, it will be understood that a single port would serve therein by circumferentially alining the ports 20 and 22 in the valve, but it is preferable to space these ports along the valve laterally of the case, so as to prevent a leakage or interference from one to the other.

I claim:

1. A valve case having a plurality of ports in one side adapted to communicate with the main supply pipe, and two ports in another side thereof, a hollow valve rotatable in the case having in one position of rotation a port in one side registering with a corresponding case port and two ports in the other side registering with the two case ports therein, and having in another position of rotation a port in one side registering with a corresponding case port and a port in the other side registering with one only of the case ports, and in another position of rotation having no ports registering with any of the case ports.
2. A valve case having two ports in one side adapted to communicate with the main supply pipe, and two ports in another side thereof, a hollow valve rotatable in the case having in one position of rotation a port in one side registering with one of the case ports and two ports in the other side registering with the two case ports therein, and having in another position of rotation a port in one side registering with one of the case ports and a port in the other side registering

with one only of the case ports, and in another position of rotation having no ports registering with any of the case ports.

3. A valve case having one or more ports in one side and two ports in another side thereof, a hollow valve rotatable in the case having in one position of rotation a port in one side registering with a corresponding case port and two ports in the other side registering with the two case ports therein, and having in another position of rotation a port in one side registering with a corresponding case port and a port in the other side registering with one only of the case ports, and in another position of rotation having no ports registering with any of the case ports; there being annular grooves extending from certain of the ports part way around the valve, to keep open communication through said ports during the rotation from the first to the second positions thereof.

HENRY E. STREIBER.
